אַתְּ־יְ

UNITED STATES PATENT OFFICE.

MARTIN CLAUSSEN, OF SAN FRANCISCO, CALIFORNIA.

ELECTRIC LAMP.

Application filed August 23, 1921. Serial No. 494,465.

To all whom it may concern:

Be it known that I, MARTIN CLAUSSEN, a citizen of the United States, residing at San Francisco, in the county of San Francisco and State of California, have invented new and useful Improvements in Electric Lamps, of which the following is a specification.

My invention relates to improvements in electric lamps, and particularly to improvements over the McKay & Claussen portable electric lamp Patent No. 1,085,147.

An object of the invention is the provision of a base cap disposed over a lamp base and vertically movable relative thereto.

15 A further object is the provision of a spiral spring for operatively forcing said base and cap apart.

A still further object is the provision of a draw-pin and lever for forcing the base and cap together against the tension of said spring.

A still further object is the provision of a novel clamping means normally concealed within the lamp base, but operatively extendible for clamping the lamp to a support, such as a table top, chair back, or other object.

20 A still further object is the provision of a novel supporting yoke carried by the lamp base and slideable laterally outwardly therefrom for suspending the lamp upon a nail, hook, or like support.

With the foregoing and still further objects and purposes in view which will appear as the description proceeds, the invention resides in the combination and arrangement of parts and in the details of construction hereinafter described and claimed, it being understood that changes in the precise 25 embodiment of the invention herein disclosed can be made within the scope of what is claimed without departing from the spirit of the invention.

In the accompanying drawings—

45 Figure 1 is a perspective view of an electric lamp constructed in accordance with my invention, clamped to the edge of a support.

50 Figure 2 is a bottom plan view of the lamp, with portions of the central members shown in section.

Figure 3 is a median sectional elevation,

with the circuit cord and the upper portion of the lamp removed.

Figure 4 is a bottom plan view of the 55 base cap, disassembled from its cooperating members.

Figure 5 is a vertical sectional view of the base cap.

Figure 6 is a bottom plan view of the lamp 60 base.

Figure 7 is a vertical sectional view of the lamp base.

Figure 8 is a bottom plan view of the reinforcing plate for supporting the upper wall 65 of the base cap.

Figure 9 is a vertical sectional elevation of the plate shown in Fig. 8.

Figure 10 is a plan view of the drum flange 70 supported by the lamp base.

Figure 11 is a vertical sectional view of the drum flange.

Figure 12 is a perspective view of the lamp fixture supporting stirrup.

Figure 13 is a bottom plan view of a portion of the lower drum cover.

Figure 14 is a sectional elevation on line 14—14, Fig. 13, the view showing the member bottom-side up.

Figure 15 is a median sectional elevation 80 of the lamp, showing the tension lever vertically disposed and the base cap extended above the lamp base as far as it can operatively go, and a section of the circuit cord wound around the cord drum.

Figure 16 is a perspective view of the tension lever.

Figure 17 is a perspective view of the draw pin sleeve.

Figure 18 is a side elevation of the draw 90 pin.

Figure 19 is a bottom plan view of the reinforcing plate in a modified form.

Referring to the drawings in detail, throughout which like reference characters 95 designate like parts—

The numeral 1 designates a lamp base, which is preferably stamped out of sheet metal and formed to provide a central upwardly projecting cord drum 2, which carries a hollow hub 3 projecting downwardly centrally into the drum and has a central opening 4 in its lower end.

The lower open end of the drum 2 is pro-

vided with a drum-head 5, which has a central opening 6 in vertical axial alignment with the opening 4, and a pair of spaced apart downwardly struck marginal indent 5 dents 7.

Downwardly into the open upper end of the hub 3 projects, rotatably, a hub 8 centrally formed upon the lower side of the drum plate 9 provided with a central opening 10 registering with the opening 4, and a downwardly struck annular marginal flange 11, which is provided at one point with a slot 12, which projects a distance inwardly into the upper horizontal wall of the plate 15 and is provided at its inner extremity with an arcuated upstanding lip 13.

14 designates a base cap, which comprises a circular flat top member 15 provided with a downwardly struck annular marginal flange 16, which is conoidal in form with its exterior side concaved and has at its lower margin an inwardly rolled annular reinforcing rib 17, a central vertical opening 18, a marginal opening 18', and a pair of laterally spaced apart slots 18'' disposed upon opposite sides of the opening 18'.

20 is a lamp fixture supporting stirrup, which has an intermediate flattened portion 21 seated against the lower side of the cap 14 and provided with an opening 22 registering with the opening 18', and a pair of flattened standards or arms 23 projecting upwardly through the slots 18'' and provided adjacent their lower extremities 35 with outwardly bent lips 24 firmly engaging the upper side of the cap for rigidly maintaining the standards in their upright position.

The free ends of the standards 23 have 40 horizontal openings 25 in which is disposed a pin 26 for pivotally supporting the lower ends 27 of a lamp fixture 28. The arrangement of the fixture 28 relative to the stirrup 20, being such that the fixture may 45 be oscillated in a vertical plane equal to approximately 180 degrees of a circle.

Into the upper end of the base cap 14 is fitted a reinforcing plate 29, which has a section abutting against the lower side 50 of the intermediate portion 21 of the stirrup 20 and an opposite portion provided with an upwardly struck spacing rib 30 abutting against the lower side of the base cap 55 for offsetting the thickness of the said portion 21, a marginal opening 31 registering with the opening 18', a central opening 32 registering with the opening 18, and a depending annular flange 33 fitted snugly against the inner wall of flange 16.

60 The base cap 14 is arranged over the base 1 in such a manner that the lip 13 will project slidably through the openings 18' and 31, and the openings 18 and 32 will be disposed in vertical axial alignment with the openings 4, 6 and 10, through which,

and also through said first named openings, projects a draw pin 34 and sleeve 35.

The lower end of the draw pin 34 is provided with an annular groove 34', while at its upper end is a suitable head 34'', which is seated upon a washer 36 disposed on the upper side of the base cap, and immediately below the head 34'' with a threaded section 37, which is provided with a nut 37' whereby the draw pin is rigidly clamped to the base 75 cap 14 and reinforcing plate 29.

The portion of the pin 34 below the threaded section 37 is diametrically reduced and projects rotatably into the sleeve 35, which is provided at its lower end with opposite openings 38 disposed in the plane of the groove 34' and through which openings project pivot pins 39 disposed eccentrically upon the inner sides of the free ends of arms 40 of a clamping lever 41. 80 The free ends of the pins 39 extend beyond the inner wall of the sleeve and movably engage the groove 34', whereby the sleeve is longitudinally retained upon the draw pin 34. 90

Encircling the sleeve 35, with its upper end pressed against the nut 37' and its lower end pressed against the bottom of the hub 8, is a spiral compression spring 42, against the tension of which plates 9 and 29 95 are held together, by means of the pin 34 actuated by the lever 41 cooperating with the drum cap 5, upon which said lever presses, when it is swung into a horizontal position in one direction (see Figs. 2 and 3). 100

The pivoted end of the lever 41 is formed so that when the lever is oscillated into a vertical position as indicated in Fig. 15, it reduces the distance between the pivot pins 39 and the drum cap 5, whereby the 105 action of the spiral spring 42 forces the drum plate 9, base 1 and drum cap 5 to move downwardly relative to the base cap 14 and reinforcing plate 29, and the lip 13 to slide vertically downwardly in the openings 18' and 31, causing a temporary separation between the lower edge of the flange 16 and an upwardly struck annular rib 43 adjacent the margin of the base 1.

The free or outer edge of the rib 43 is 115 concaved upon its inner side, except for a small portion thereof which is flattened upon its outer side, thereby forming a depending base-front 44, which is provided with a pair of laterally spaced apart openings 45, 120 through which slidably project the side arms 46 of a supporting yoke 47, which arms also slidably project through the indent 7 and into the drum 2 where their free ends are bent upwardly to form standards 46'. The outer ends of the arms are unitarily joined together by an intermediate portion 125 disposed exteriorly of the base-front 44.

48 designates a clamping spring having a circular portion 49 confined against the 130

tension of itself in the concaved portion at the outer edge of the rib 43, and intermediate sections 50, adjacent the base-front 44, doubled backwardly and rotatably 5 clamped to the lower side of the base 1 by means of clamping lips 51 struck out of said base, and oscillating arms 52, which cross and extend parallel to each other across the body of the base with their free 10 ends bent forwardly to form a pair of laterally spaced apart clamping fingers 53.

54 is a lamp cord, embodying circuit wires 54', which cord has one end suitably connected to the lamp fixture 28, from whence 15 it extends through the openings 18', 22 and 31, through the slot 12 and to and around the drum 2 and thence out through a notch 55 formed in the apex of the rib 43 above the base-front 44, the notch 55 being formed 20 by pressing downwardly a portion of the walls of said rib 43.

In Figure 19 is shown a reinforcing plate differing from the one shown in Figures 8 and 9, to the extent that it is provided 25 with an additional spacing rib 30'.

To operate my improved lamp for winding or unwinding the cord 54, the lever 41 is swung into a vertical position as indicated in Fig. 15, thereby permitting the 30 spring 42 to function, as heretofore mentioned, to vertically separate the outer edge of the flange 16 from its normal position against the rib 43, and permitting the cord to be removed from the notch 55, when it 35 may be passed around between the rib 43 and flange 16 the required number of times to either wind it upon or unwind it from the drum 2.

To operate the lamp for clamping it to a 40 support, the clamping fingers 53 are drawn out from their normal position against the bottom of the base 1, against the yielding resistance of the twist tension of the intermediate sections 50, amplified by the resiliency 45 of the spring in general, and are then permitted to operatively engage the opposite side of any suitable support to which it may be desired to secure the lamp, such as the edge of a table, back of a chair, bed standard, or 50 any other suitable article, without regard to the incline or position of such article.

For supporting the lamp by hanging, the supporting yoke 47 is drawn horizontally outwardly from the side of the base by sliding 55 the arms 46 out through the openings 45 and along the indents 7 until the standards 46' engage the wall of the drum 2, when the intermediate section 47' may be hooked over a nail, hook, or other suitable projection.

60 While the stirrup 20 is rigidly secured to the base cap 14, available rotation of the lamp fixture 28 in a vertical plane about the axis of the pivot pin 26, is equal to 180 degrees, or more, of a circle.

65 Having described my invention what I

claim and desire to secure by Letters Patent, is:

1. In an electric lamp of the character described, a lamp base having an upwardly projecting central cord drum and an upwardly struck annular marginal rib having a notch formed in its apex adapted to receive a lamp cord operably windable upon said cord drum. 70

2. In an electric lamp of the character described, a lamp base having an upwardly projecting central cord drum and an upwardly struck annular marginal rib having an indentation in its apex, and a lamp cord extending slidably through said indentation and having a portion normally wound around said drum, said indentation being formed by striking downwardly a portion of said marginal rib without cutting out the metal forming same, whereby the walls of said indentation may form a slide-way for the passage therethrough of said lamp cord. 80

3. In an electric lamp of the character described, a clamping spring having an intermediate portion secured to the bottom side 90 of the lamp base and having a pair of arms extending parallel across said bottom side, the free ends of said arms operatively swingable downwardly against the tension of said spring. 95

4. In an electric lamp of the character described, the combination with a lamp base having a central drum upon its upper side, the drum provided with a central downwardly projecting recess, of a drum plate 100 disposed over the drum and having a central hub projecting into said recess.

5. In an electric lamp of the character described, the combination with a lamp base having a cord drum disposed centrally upon its upper side, an inwardly projecting hub on the upper end of the drum, the hub open at its upper end and provided at its lower end with a central opening, of a drum plate, 105 spring pressed against the upper end of the drum and provided with a centrally disposed hub on its lower side projecting downwardly into said first named hub and having an opening in its lower end in axial alignment with said first named central opening. 110

6. In an electric lamp of the character described, the combination with a lamp base having a hollow bottom, of a clamping spring concealed in said bottom and having an intermediate portion permanently secured to the walls thereof for supporting it, the ends of said spring terminating in a pair of laterally spaced apart and approximately parallel clamping fingers, said fingers operatively swingable downwardly below said base. 120

7. In an electric lamp of the character described, the combination with a lamp base having a central hollow drum on its upper side, the drum open at its lower end, the base 125

- provided adjacent its margin with a pair of laterally spaced apart horizontal openings, of a supporting yoke having intermediate portions horizontally slidably disposed in said openings and having its inner portions bent upwardly and engageable with the inner wall of said drum for limiting the longitudinal movement of the yoke in one direction.
8. In an electric lamp of the character described, the combination with a lamp base having an annular margin concaved on its inner side, of a clamping spring having its circular body portion secured to said annular margin, intermediate portions of the spring clamped to the lower side of the base, arms upon said intermediate portions, and fingers upon the free ends of the arms.
9. In an electric lamp of the character described, the combination with a circular lamp base, the outer margin of the base concaved on its inner side, of a clamping spring, the clamping spring having an outer circular body spring pressed into said concaved portion of the margin for securing it to the base, intermediate portions of the spring bent inwardly and disposed against the lower side of the base, and means carried by the base for clamping said intermediate portions to the base, the free ends of said intermediate portions bent to form arms swingable downwardly against the tension of the spring, the free ends of the arms provided with clamping fingers.
10. In an electric lamp of the character described, the combination with a lamp base having an annular downwardly projecting wall at its margin, the lower extremity of said wall concaved, of a clamping spring having a circular body portion pressed against the tension of itself into said concavature at the lower extremity of the wall, extensions of said spring disposed inside said circular body portion and in the same horizontal plane, the free ends of said extensions operatively swingable downwardly in a vertical plane against the tension of the spring, and means for securing portions of the extensions to the lower side of the base.
11. In an electric lamp of the character described, the combination with a lamp base having portions of its upper wall apertured to form lips having their free ends projecting below said wall, of a clamping spring disposed inside the base and secured to the lower side of said wall by means of said lips, oppositely disposed inner terminals of the spring operatively swingable downwardly in a vertical plane against the tension of the spring, the free ends of said terminals converging along the line of an arc when said terminals are operatively swung downwardly.
12. In combination, a lamp base having a hollow cord drum projecting upwardly centrally from its upper side, the upper wall of said drum being concaved thereby forming a hub projecting down into said drum, a drum head engaging the lower side of said lamp base adjacent the margin of the lower end of said drum, the lower end of said hub terminating short of said drum head, and means for holding said drum head against said lower side of the lamp base.
13. The combination with a lamp base having a centrally disposed upwardly extending recess formed in its upper wall, of a drum head engaging said upper wall adjacent the margin of said recess for closing it, said drum head having a pair of laterally spaced apart indentations in its margin wherein are slidably supported the side arms of a lamp supporting yoke, the free ends of said arms being bent upwardly and operatively movably disposed in said recess and engageable with the side walls of said recess for limiting the longitudinal movement of said arm in said indentations.
14. The combination with a lamp base having a downwardly projecting annular flange upon its margin and a cord drum open at its lower end projecting upwardly from its center, said flange having a pair of laterally spaced apart openings, of a supporting yoke formed by bending a wire into two parallel members projecting slidably through said spaced apart openings and unitarily joined together upon the exterior of the lamp base, the inner ends of said parallel members bent upwardly into said cord drum, and a drum head for movably supporting said inner ends of the parallel members.
15. The combination with a lamp base having a downwardly projecting annular flange upon its margin and a cord drum open at its lower end projecting upwardly from its center, said flange having a pair of laterally spaced apart openings, of a lamp supporting yoke comprising an outer portion disposed exteriorly of the lamp base and having a pair of inwardly extending members projecting slidably through said spaced apart openings and having their inner ends turned upwardly into said open end of the cord drum, a drum head having marginal indents through which said inwardly extending members operatively move, and means for holding said drum head against the lower side of said cord drum.
16. In an electric lamp of the character described, in combination, a base cap having a pair of laterally spaced apart slots extending vertically through its upper wall, a fixture supporting stirrup having a pair of side arms projecting up through said slots and an intermediate portion for rigidly connecting the lower end of said side arms together, said intermediate portion adapted to seat against the lower side of said upper

wall of the base cap, and means on said arms engaging the upper side of the wall for holding said intermediate portion firmly against said lower side.

5 17. In an electric lamp of the character described, a lamp fixture supporting stirrup embodying a pair of laterally spaced apart flat side arms, an intermediate section unitarily connecting the lower ends of said side 10 arms together, and a projection upon one side of each of said arms, said projections spaced a distance upwardly from said intermediate section.

18. In an electric lamp of the character 15 described, in combination, a base cap having a vertical opening in its center and a vertical opening adjacent its margin, and a reenforcing plate having a central opening registering with said first named opening in the 20 base cap and a marginal opening registering with said second named opening in the base cap.

19. In an electric lamp of the character 25 described, in combination, a base cap, a drum plate disposed inside the base cap, a central opening in said drum plate disposed in axial alignment with a central opening in the base cap, a draw pin projecting through said openings, the base cap provided with a marginal opening, and means on the upper side of said drum plate projecting through said marginal opening for preventing rotation of 30 said drum plate about its vertical axis relative to the base cap.

25 20. In an electric lamp of the character described, in combination, a lamp base, a base cap, a spring for yieldingly forcing said base and base cap away from each other, and means for operatively forcing said base 40 and base cap towards each other against the tension of said spring.

21. In an electric lamp of the character 45 described, in combination, a lamp base having a central vertical opening, a base cap having a central opening in axial alignment with said first mentioned opening, a pin projecting through said openings and having its upper end rigidly secured to the base cap, a coil compression spring disposed between 50 said lamp base and base cap for operatively forcing them vertically apart, and means engaging the lower end of said pin for forcing said base and base cap together against the tension of said spring.

55 22. In an electric lamp of the character described, in combination, a lamp base having an opening extending vertically through its center, a drum plate having an opening extending vertically through its center, a cord drum disposed centrally between said drum plate and lamp base for vertically spacing the outer portions of said members a distance apart, and a pin projecting through said openings.

60 23. In an electric lamp of the character

described, in combination, a lamp base having a drum plate disposed above it, a cord drum disposed centrally between said base and plate for spacing them vertically a distance apart, means for securing said cord 70 drum and drum plate and lamp base together, and a lamp cord on the drum.

24. In an electric lamp of the character described, in combination, a lamp base having a drum plate disposed above it, a cord 75 drum disposed centrally between said lamp base and drum plate for spacing outer portions of said elements vertically a distance apart, said drum rigidly secured to one of said elements, a circuit cord carried by the 80 lamp and windable upon said drum, and means for rotatably securing said lamp base and drum plate together.

25. In an electric lamp of the character 85 described, in combination, a lamp base having a drum plate disposed above it, a cord drum disposed centrally therebetween for vertically spacing said members a distance apart, means for pivotally connecting said lamp base and drum plate together, and a 90 circuit cord carried by the lamp windable on said drum.

26. In an electric lamp of the character described, in combination, a lamp base, a 95 cord drum disposed above the lamp base, a base cap disposed above the cord drum and vertically movable relative thereto, and a circuit cord having a portion extending through said base cap and another portion 100 operatively windable on said drum.

27. In an electric lamp of the character described, in combination, a lamp base, a base cap disposed above said base and having a downwardly projecting annular marginal flange normally seated upon the margin of 105 the base, and a spring disposed between said base and cap for operatively forcing said members vertically apart.

28. In an electric lamp of the character 110 described, in combination, a lamp base, a base cap disposed above said base and having a downwardly extending marginal flange normally seated upon an outer portion of said base, a pivotal connection between said base and base cap, and a compression spring 115 for operatively forcing said base and base cap vertically away from each other.

29. In an electric lamp of the character described, in combination, a lamp base, a base cap disposed above said lamp base and having a downwardly extending marginal flange normally seated upon the rim thereof, a draw pin for pivotally connecting the lamp base and base cap together, and a spiral compression spring encircling said draw 120 pin and operable for yieldingly forcing said marginal flange and rim vertically apart.

30. In an electric lamp of the character 125 described, in combination, a lamp base, a base cap disposed above the lamp base and

having a downwardly extending marginal flange normally closed down upon the rim thereof, a cord drum disposed inside the lamp, a spring for operatively forcing said 5 marginal flange vertically away from said rim, said spring disposed inside the cord drum, and means for operatively forcing said marginal flange downwardly upon said rim against the tension of said spring.

31. In an electric lamp of the character described, in combination, a lamp base having an annular rim provided with a notch on one side, a base cap disposed above the lamp base and having a downwardly extending 10 marginal flange, a cord drum disposed centrally between said lamp base and base cap, a circuit cord having an intermediate portion wound upon said rim with one end projecting up through said base cap and another end normally disposed in said notch, a spring for operatively forcing said marginal flange vertically upwards from said 15 rim to form an annular slot therebetween, whereby said cord may be removed from said notch and passed along said slot for winding it upon the drum, and means for forcing said marginal flange and rim operatively together against the tension of said 20 spring for closing said slot against the passage of the cord therein.

32. In an electric lamp of the character described, in combination, a lamp base adapted for normally supporting the lamp, a base cap disposed above said lamp base 25 and adapted for supporting a lamp fixture upon its upper side, a spring disposed between said lamp base and base cap adapted for forcing said lamp base and base cap away from each other as far as they can go, 30 and means operable against the tension of

said spring adapted for forcing said base cap and lamp base towards each other as far as they can go.

33. In an electric lamp of the character described, in combination, a lamp base 45 adapted to normally support the lamp, a base cap adapted to support a lamp fixture upon its upper side, a resilient element confined against the tension of itself between said lamp base and base cap and adapted for 50 yieldingly forcing said lamp base and base cap away from each other, and means for operatively forcing said lamp base and base cap towards each other against the tension of said resilient element. 55

34. In an electric lamp of the character described, a base cap comprising a flat top and an annular downwardly extending side wall, said top having a vertical central opening and a vertical marginal opening and a 60 pair of parallel vertical slots disposed one on each side of said marginal opening, said slots disposed in vertical planes extending on opposite sides of the vertical axis of the base cap. 65

35. In an electric lamp of the character described, a base cap having a central vertical opening and a marginal vertical opening, an element projecting through said central opening for securing said cap to the lamp, a lamp fixture supporting stirrup having a portion engaging said base cap, said portion provided with a vertical opening registering with said marginal opening, and means for 70 rigidly securing said stirrup to said base cap. 75

In testimony of the foregoing being my own, I have hereunto affixed my signature this 13th day of August, 1921.

MARTIN CLAUSSEN.
